NOISELESS TYPEWRITER REACH ADJUSTMENT AND ESCAPEMENT MEANS

Evert G. Israelson, Rowayton, Conn., assignor to Sperry Rand Corporation, New York, N. Y., a corporation of Delaware

Application March 12, 1956, Serial No. 570,978

15 Claims. (Cl. 197—17)

This invention relates to writing machines of the power operated noiseless type, and in particular to control of the escapement mechanism thereof.

In noiseless type actions of the kind shown in U. S. Patent 1,574,285 and in the power mechanism for operating the same, as disclosed in an application of common assignee Serial No. 412,208 filed February 24, 1954, the key controlled power operating mechanism is effective to apply an initial impetus to the type bar organization to an extent defined as a "reach zone" during which time the type bar mechanism is being operated positively by said power mechanism. Beyond the "reach zone" the type bar mechanism is propelled by the action of a pivoted weight or momentum accumulator to complete the printing stroke free of the influence of the power mechanism. As shown in the patent referred to, the escapement is controlled by the action of the type bar mechanism and the escapement load tends to dampen the momentum imparted to the type by operation of the weight.

An object of the invention therefore is to provide means for operating the escapement without in any manner effecting the thrust operation of the type mechanism or by placing a load thereon that would decrease the speed of operation.

A further object of the invention is to so actuate the escapement mechanism from the power mechanism that, in the initial stage of operation of the latter, power will not be applied to the escapement operation and the full thrust of the type will be unrestrained.

Still further objects of the invention are: to closely define the limits of power applied to the type bar mechanism and to adjust the operation of the escapement so that it occurs at precisely the proper time with respect to the printing operation of the type bars; to provide for adjustment of the reach zone so that each individual type bar action and its power mechanism can be closely coordinated in action, to make use of said adjustment to control the timing of the escapement action; and to free the type action for full thrust so that not only speed and accuracy of typing are attained but maximum manifolding is possible in a machine of the noiseless type.

Other objects and structural details of the invention will be apparent from the following description when read in connection with the accompanying drawing in which

Fig. 1 is a view in side elevation of the type bar mechanism as employed in a noiseless typewriter and the power mechanism used in the operation thereof; the escapement control being indicated, the view showing the parts in normal non-operating position;

Fig. 2 is a view similar to Fig. 1 showing the parts in the position they assume at the end of the movement controlled by the reach stop limit means;

Fig. 3 is a view similar to Fig. 1 showing the parts just after printing impact and illustrating the operation of the escapement mechanism beyond the reach stop zone operation of the type action; and

Fig. 4 is a section taken on the line 4—4 of Fig. 2 show-

2

ing the foot portion of one throw arm of a type action and the relative positions of the associated sublevers.

Referring to the drawings in detail 10 indicates generally the frame of the machine to which may be pivoted as at 11 the type bar segment 12 which, in the well known manner is adjustable to shift the case of the different characters "Ee" and "Xx" carried on the faces of the forward bifurcated portions 13 and 14 of the type bar 16 which is pivotally mounted on the upper ends of guide links 17 and 18. In view of the fact that the type bar action 20 is common in principle to the type bar action of the Remington Noiseless Typewriter, as disclosed in the above patent, only sufficient explanation of the parts will be given herein to show the operation as employed in combination with the power mechanism 19 controlled by the keys 21 and generally shown in Patent 2,638,199. Each unit of the type bar action 20 consists of a single type bar 16 operable to print two different characters and, with its operating levers, is mounted on a hanger 22 secured to the type bar segment 12. Each type bar is guided in the slots 23 of a segmental shaped guide 24 mounted on the rear portion of the bar segment 12 and is thrust forward in printing action by the operation of twin throw arms 26 pivoted to said hanger and connected across their foot portions 27 by a curved rocker plate 28. The latter has bearing thereon, in rocking engagement, the cam shaped ends 29 and 31 of sublevers 33 and 32, respectively, the former of which is extended as at 34 for connection, through a link 35, with a bell crank lever 36 pivoted as at 37 on an extension 38 of said hanger 22. The limit of the swinging movement of the sublever 33 about its pivot 39 is defined by a pin and hole combination or reach stop 40, and a similar movement limiting arrangement 41 is employed in connection with the sublever 32. The movement of the sublevers alters the position of the pivot at the lower end of the guide link 18 so that the different type "e" or "x" are projected for writing on the platen 42 depending upon which sublever is pulled down by its depending link. The sublever 32 is connected by a link 43 with one end of an operating roller lever 44 while the sublever 33 is connected by a link 46 with a similar operating lever 47. The levers 44 and 47, each carrying a roller 48, are pivoted as at 49 in the lower portion of the bar segment and are paired with respect to each type bar action 20. Each lever is biased upwardly at its link supporting end by a spring 51 which also keeps the respective roller in surface contact with the working edge 52 of an operating lever bar 53, one of each of which is provided for each operating lever and for each power mechanism unit 19.

In Fig. 1, two keys 21 are shown, each of which is connected to and controls the operation of its power mechanism unit 19. Generally, each unit derives its power from a constantly driven power roll 54 so that when an eccentric roller 56 is rotated into engagement therewith by operation of a key lever controlled train of parts 57 as shown in Patent 2,638,199 a power arm 58 is lifted and through a stud 59 rocks a bell crank cam 60 clockwise against the resistance of a spring 61. The bell crank 60 is shaped to provide, on a lower free depending edge, a cam surface 62 terminating in a cam dwell 63 for operational engagement with a cam roller 64 carried on a cam lever 66 pivoted as at 67 to a vertical operating link 68. The latter is pivoted to the inner end of the operating lever bar 53 to pull the latter in tilting movement about its fulcrum rod 69 which, like the fulcrum rod 71, is common to the parts mounted thereon and is supported from one of a plurality of cross bars 72 extending between the side frames of the machine.

Each cam lever 66 is connected by a link 73 with the upper portion of an adjusting dog 74, mounted on a pivot rod 76 in the lower cross bar 72, and shaped to provide

a toe portion 77 which is biased by spring 61 against adjusting screw 78 in said cross bar. The purpose of this adjusting means, designated generally by numeral 75, will be brought out hereinafter. The fulcrum rod 71 also supports, for swinging movement, a pair of bail brackets 79 having a stop extension 80 thereon, which brackets carry between them a rod 81 for support of an escapement bracket 82, near the center of the machine to which one end of an escapement tie link 83 is pivoted, as at 84. The bail brackets 79 support an escapement bail 86 common to all of the forward vertical edges of the bell crank cams 60. The escapement (Fig. 3) includes the carriage rack pinion 87 and escapement wheel 88 mounted on a common stud shaft 89 fixed in a frame supported by bracket 91, the side ears 92 of the latter of which provide strunnions for the pivotal support of a dog rocker 93. The latter carries a pivoted dog 94 which releases the wheel in the well-known manner when the rocker is tilted on its axis to permit the wheel to move an amount in carriage spacing action determined by the alternate actions of a toe portion 95 formed on the rocker and a limited yield of said dog. The rocker at its lower edge is connected by the escapement link 83 with the bracket 82 to the latter of which it is pivoted as above described. The end of the link 83 is threaded to receive a nut 97 to afford adjustment of the rod or link 83 with the rocker 93. The escapement was previously controlled by the operation of a bail link from the throw arms 26 of the type action. When these arms are thrown forward by operation of either of the sublevers 32 or 33 they swing a momentum accumulating weight 98 forward so that its extended portion 99 which is pivoted to a toggle link 100 will impart a forward thrust to a toggle link 101 to project the type bar 16 forward in printing action. The extent of drive force applied to the throw arms 26 is limited by the reach stops 40 and 41. In Fig. 1 the parts are in normal position and when the letter "e" key is operated the power mechanism corresponding thereto swings the bell crank cam 60 clockwise to depress the link 68 and through lever bar 53, roller 48, lever 47 and link 46 swing the sublever 33 counterclockwise to rock the throw arms 26 to the position shown in Fig. 2. At this point the pin of the reach stop combination 40 will halt the movement of the sublever 33, and the momentum of the swinging weight 98 will thrust the type bar 16 against the platen. When the escapement was operated from the throw arms the drag on the latter had a slowing down effect on the operation of the weight and the forward thrust of the type bar 16 was damped with a resultant decrease of printing impact. In the present instance the escapement is not fully operated until after printing occurs because the bail 86 is not initially actuated by the bell crank cam 60 (Fig. 1) and is only contacted by the latter (Fig. 2) when the cam roller 64 reaches the dwell 63 after full momentum has been imparted to the weight 98 by forceful operation of the throw arms through the power mechanism 19.

The adjusting dog 74 coacts with the screw 78 to limit the downward movement of link 68, to provide a positive action free from overthrow and to enable each reach stop to be accurately adjusted to allow complete printing impact by the type before the escapement is actuated to cause letter space movement of the platen. This adjustment is made by turning the screw 78 so that, when the roller 64 is at the dwell 63 of cam 60 the pin 40 of the reach stop 41 is in position to arrest any further movement of the respective sublever, substantially as illustrated in Fig. 2. Thereafter the continued swinging movement of the bell crank cam 60 will, under force of the power mechanism, cause operation of the escapement as shown in Fig. 3. When the screw 78 is turned, the dog 74, if being adjusted counterclockwise, will pull on link 73 to cause the roller 64 to engage the dwell 63 of the cam 60 and at the same time pull down on link 68. The latter, as above explained, will rock the associated sublever until

the pin of the reach stop associated with said sublever is in its limit position. The adjustment is made by rocking the cam 60 until the dwell thereof is in position to be engaged by the roller 64 when the latter is forced into contact therewith by operation of the screw 78. At the same time the link 68 is pulled down and the link 46 swings the sublever 33, for instance counterclockwise until the reach stop as shown in Figs. 2 and 3, limits the movement of the sublever. The dwell 63 of cam 60 is not perfectly concentric with the pivot 71 but has a slight radial pitch which keeps the reach stop in its limit position and consequently prevents any change in location of the parts that have been set by the operation of the sublevers for proper pivotal throw of the type bars under influence of the momentum weight 98. While the adjusting means 75 has been described in connection with the escapement means it is evident that it can be employed for reach stop adjustment to take up wear and generally define the power operation and weight accelerated thrust action.

While I have described what I consider to be a highly desirable embodiment of my invention, it is obvious that many changes in form could be made without departing from the spirit of the invention, and I, therefore, do not limit myself to the exact form herein shown and described, nor to anything less than the whole of my invention as hereinbefore set forth and as hereinafter claimed.

What I claim as new, and desire to secure by Letters Patent, is:

1. In a typewriter, the combination with a key controlled power means and a noiseless type action operated thereby and including reach stop means for arresting the force applied to the action by said power means; of a train of parts connecting said power means and said type action, including operating link means; cam means actuated by said power means, and an adjusting means connected to said link means and operated by said cam means for varying the force arresting operation of said reach stop means.
2. In a typewriter having an escapement mechanism for controlling letter spacing movements of a platen, a noiseless type action for printing on said platen, a key controlled power means, a train of parts connecting said power means with the type action for operating the latter with an initial power thrust, said train of parts including a cam, and means operated by said cam after said initial power thrust is completed by said type action for controlling the operation of said escapement mechanism.
3. In a typewriter having an escapement mechanism for controlling letter spacing movements of a platen, a noiseless type action for printing on said platen, a key controlled power means, a train of parts connecting said power means with said type action for operating the latter, said train of parts including a cam, means operated by said cam for controlling the operation of said escapement mechanism, and stop means for initially positioning the escapement control means in spaced relation to the cam for rendering said escapement control effective after a predetermined operation of said cam.
4. In a typewriter, the combination with a key controlled power means and a noiseless type action operated thereby and including reach stop means for limiting the extent of force applied to said action by the power means; of a train of parts connecting the power means and the type action including a cam operated by said power means, and an adjusting means actuated by said cam for varying the extent of force as controlled by said reach stop means.
5. In a typewriter, the combination with a key controlled power means, a noiseless type action operated by the power means including reach stop means for defining the extent of force applied to the action by the power means, and an escapement mechanism for controlling letter spacing movements of the platen; of a train of parts

including cam means connecting the power means and the type action, and means associated with said cam means and operated thereby for controlling the operation of said escapement mechanism in coordination with the operation of said reach stop means.

6. In a typewriter having a type action including reach stop means for defining the limit of an initial movement of said action, key controlled power means for applying said initial movement to the action, movement transmitting means connecting the power means with said action, including an operating link, a bell crank pivoted to said link, a bell crank cam for operating said link through throw of said bell crank and means for manually adjusting the amount of throw of said bell crank to vary the limit of initial movement of said action through said reach stop means.

7. In a typewriter having an escapement mechanism for controlling letter spacing movements of a platen, a type action, key controlled power means for applying operating force to the action, said action including reach stop means for arresting the force applied thereto, linking means connecting said power means with said action including cam means operated by the power means, escapement operating bail means common to said cam means and adapted to be operated by the latter at the end of a predetermined amount of movement thereof, and means associated with said cam and linking means for adjusting the reach stop means in accordance with the predetermined movement of said cam means.

8. In a typewriter having an escapement mechanism for controlling letter spacing movements of a platen, a type key controlled power means for applying operating force to the action, said action including reach stop means for arresting the force applied to said action, linking means connecting said power means with said action including a cam operated by the power means, escapement operating bail means common to said cam and adapted to be operated by the latter, means for normally holding said bail means spaced from the cam, and means associated with said linking means and said cam for adjusting the reach stop means to force arresting position when the cam engages said bail means.

9. In a typewriter having an escapement mechanism for controlling letter spacing movements of a platen, a type action; key controlled power means for applying operating force to the action, said action including reach stop means for arresting the force applied to the action; means connecting said power means with said action including cam means actuated by the power means, an

operating link means, and adjusting means connecting the link means with said cam means; and escapement bail means common to said cam means for operation by the latter to actuate said escapement mechanism.

5 10. A typewriter of the character set forth in claim 9 in which said cam means presents a rise portion, a dwell portion and a portion for engaging said escapement bail means when said adjusting means is substantially at the junction of said rise and dwell portions of the cam means.

11. A typewriter of the character set forth in claim 10 in which said cam means beyond the dwell portion thereof provides a slight radial rise for maintaining said reach stop means at force arresting position and for taking up lost motion in the parts of said action.

12. A typewriter of the character set forth in claim 9 in which said cam means presents a rise portion, a dwell portion and a portion for engaging said escapement bail means when said adjusting means is substantially at the junction of said rise and dwell portions of the cam means and the reach stop means is in force arresting position.

13. A typewriter of the character set forth in claim 9 in which said adjusting means comprises a cam roller carrier pivoted to said link means, a pivoted adjusting dog, a link joining the dog and the carrier, and screw means for moving the carrier through said dog and joining link for adjusting the reach stop means with respect to said escapement bail means.

20 14. A typewriter of the character set forth in claim 9 in which said escapement bail means comprises bracket means mounting the bail for pivoted movement toward and away from said cam means and a stop associated with said bail means for limiting the movement of the bail means toward said cam means and for holding the bail means spaced from said cam means when the latter is in normal non-operating position.

25 15. A typewriter of the character set forth in claim 9 in which said adjusting means comprises a cam roller carrier pivoted to said link means, a spring biased dog pivotally associated with said carrier, and means for adjusting the carrier through said dog for regulating the reach stop means with respect to the relative positions of said cam means and escapement bail means.
